UNITED STATES PATENT OFFICE.

ALBERT F. BEMIS, OF NEWTON, MASSACHUSETTS, ASSIGNOR TO BEMIS INDUSTRIES, INC., OF BOSTON, MASSACHUSETTS, A CORPORATION OF DELAWARE.

BUILDING CONSTRUCTION.

Application filed December 2, 1925. Serial No. 72,674.

In my copending application No. 33,173 filed September 12, 1925, I have shown various means for joining columnar units to form the basic structure of the walls, floors, 5 roofs, etc. of a building, while in my copending applications Nos. 72,673 and 72,678 filed of even date herewith I have shown further means for combining units for such a purpose.

10 The present invention relates to similar subject matter, more particularly to an advantageous method of joining columnar units to adjacent parts of the structure and of aligning these members. One aspect of the 15 present invention concerns the provision of projecting means upon a frame member to interlock with recesses or slots in standardized tubular units of any of the various forms described in my copending applications Nos. 20 72,676 and 72,675.

A further aspect of this invention concerns the application of rangers to recessed portions of these units at their upper ends.

The novel means provided for securing the 25 ends of the units provides a method for holding them against transverse movement, of aligning them accurately, and of keying them to the surrounding structure with the minimum expense and requirement for accurate 30 workmanship. When used in conjunction with a foundation or the like such a method provides a joint capable of excluding moisture at this point, while when used with inclined units, such a method will also aid 35 in holding the units against endwise movement. If desired means such as slots may be provided on the projecting portion of the frame member to hold the units at desired 40 intervals. This mode of incorporating stand- ardized units in a building structure has the 45 particular advantage that the portions of the combination requiring accurate work- manship can be prepared in advance in a manufacturing establishment and can then be readily assembled in situ by comparatively unskilled labor.

Many further advantages of this invention will be apparent to those skilled in the art, upon a reading of the subjoined description 50 and claims in connection with the accompanying drawings.

In the drawings:

Fig. 1 is a cross-section of the side wall and a portion of the floors and roof of a 55 building;

Fig. 2 is a perspective view of a series of wall units;

Fig. 3 is a perspective view of a portion of a modified form of foundation;

Fig. 4 is a similar view of a further modification of my invention;

Fig. 5 is a view similar to Fig. 2 of a series of slightly different wall units;

Fig. 6 is a detail view of a modification of my invention; and

Fig. 7 is a view similar to Fig. 2 of a slightly different construction.

In accordance with the embodiment of my invention, disclosed more particularly in Figs. 1, 2 and 5, a foundation 2 is poured or otherwise formed with the elongate key member 3 inset in the upper surface thereof. The member 3 may be of wood or light cementitious material and has a lower portion set in a depression 4 in the foundation 2 and an upper portion which is adapted to be engaged in slots 5 formed in the ends of the structural units 1. These structural units 1 may be of the tubular form described in my copending application No. 72,678 or they may be of numerous other forms, such as illustrated in Fig. 5 or described in my other above identified applications. To form a wall, the units 1 are dropped in place with the slots 5 engaging the key member 3, thus holding them against transverse movement and substantially aligning them, and also constituting means for preventing the seepage of moisture above the base member. The member 3 may have slots 7 in the upper face thereof (Fig. 5) suitably spaced to engage the walls of the units 1 the slots 5 and 7 together forming means for interlocking the units and the foundation to hold the former against movement. The slots 5 in the ends of the tubular units may be preformed at the factory or manufacturing establishment where the units are made. The member 3 may be similarly produced to interfit with the walls of the units 1 so that, when a structural wall or the like is to be erected, these parts can be easily assembled.

In the upper ends of the structural units, slots 5 are provided which are preferably of the same size as those in the lower ends of the units so that upon assembly the ends of the units may be readily interchanged, although, if desired, the dimensions of the slots may be varied to suit individual conditions. Fitted in the slots 5 at the upper end of the units 1

is an elongate ranger 6 which is similar to the key member in the lower slots. When desired, such a ranger may also have slots 7, like those in the key member 3, to engage the 5 walls of the units.

A floor 8 of any desired form or a roof may be built adjacent the tops of the units 1, and preferably has a concrete girt connected thereto above the structural units 1. A portion 10 of the ranger 6 is extended upward into the girt 9, thereby holding the structural units to that member. At either side of the ranger 6 are capping strips 13 covering the ends of the units 1, with openings at intervals therealong, if desired, to permit the filling of certain tubular units with concrete. The outer portions of the units 1 may be covered with a layer of cementitious material 11 or with any finishing material.

20 If it is desired to add another story, a key member 3, which is similar to that previously described as incorporated in the base 2, is inset in the girt 9 to engage the lower ends of another series of units. If it is desired to 25 form a pitched roof such as illustrated in Fig. 1, a key member 15 is inset in the upper girt 14 in the manner that has already been described; this key member may have an outer bevelled surface 17 with an inclination 30 approximating the pitch of the roof. The units 1^a, which are to form the basis of the roof fabrication, are notched at 16 to engage key member 15 which serves not only to align the tubular units but also to aid in keeping 35 them from endwise movement. As a consequence of such a function this key member 15 is preferably somewhat stiffer than key member 3 previously described.

40 Fig. 3 shows a slightly different form of my invention wherein the key member 3^a is integrally cast in the upper surface of a foundation or girt 19 and is adapted to engage slots of structural units in the manner described above. If desired transverse slots 45 may be molded in this integral key member.

Fig. 4 shows a metal key member 17 with a beaded lower edge 18 adapted to be inset in a concrete foundation and be similarly engaged in slots in structural units. Such a 50 member is adapted to form a permanent weather-tight joint and readily permits the formation of slots 7, such as have been described above.

Fig. 6 shows a means of combining the 55 ranger and the capping strips for the tops of tubular units 1, the capping strip 20 and ranger 21 being secured together in a unit and fitted upon the upper ends of the structural units in a single operation. With this 60 arrangement the strip 20 is preferably a single piece extending the full width of the units 1 and the ranger 21 does not project into the

girt member but is secured to the lower surface of the capping strip or formed integrally therewith.

65 An alternative mode of construction is illustrated in Fig. 7, the base 22 having a raised portion 23 substantially equal to the distance between the opposite flat walls 28 and 29 of structural units 31. The transverse 70 walls 35 of these units are cut away at 25 to permit the inner and outer walls 28 and 29 to straddle the raised portion 23. L-shaped metal strips 33 preferably are inserted between the portion 23 of the base and the walls 75 28 and 29 to protect the construction against moisture. At their upper ends the outer walls 29 are extended upwardly to constitute a form for the pouring of a concrete girt member 39, which may be engaged with a 80 ranger 6 of the type previously described.

Obviously the embodiment of my invention disclosed in this application may be combined with the various units and modes of construction described in my copending 85 applications, as well as with many common and conventional forms of building construction now known to the art, in a wide variety of ways to suit individual conditions.

90 I claim:

1. In a building construction, means for securing elongate juxtaposed tubular units to a frame member consisting of an elongate key member inset in the frame member and extending into slots in the ends of walls of the 95 units and being slotted to engage said walls.

2. In a building construction including a frame member and a series of juxtaposed tubular units, a narrow elongate portion projecting from said frame member and having 100 slots which engage with the ends of the walls of the tubular units.

3. In a building construction including a frame member and a series of juxtaposed tubular units, a narrow elongate key portion 105 projecting from said frame member, said key portion having slots to engage the walls of the tubular units, said walls having slots to engage the key portion, to permit the key portion to intersect the ends of the tubular 110 members.

4. In a building construction including a frame member and a series of juxtaposed tubular units, an elongate key portion projecting from said frame member and being 115 slotted to engage with the ends of certain walls of the tubular members, certain walls of the tubular members being slotted to engage with the key portion of the frame member.

120 Signed by me at Boston, Massachusetts, this 30th day of October, 1925.

ALBERT F. BEMIS.
